UNITED STATES PATENT OFFICE

2,561,880

COIN AND CHECK SEPARATOR

Frank G. Nicolaus, Walter M. Burnside, and Nels A. Nelson, Chicago, Ill., assignors to Raymond T. Moloney

Application December 23, 1946, Serial No. 717,968

4 Claims. (Cl. 133—3)

1

This invention pertains to coin and check handling devices and has as its principal object the provision of an electromagnetically actuated check and coin separating device especially suited for use with coin and check-operated machines and operating to direct coins and checks into different receptacles.

Another object is the provision of a check and coin separating mechanism in the form of a unit removably attached to a coin or check stacking tube.

A further object is the provision of a coin or check receiving or stacking tube having an especially formed mouth or throat adapted to prevent jamming when the tube is full.

Yet another object is the provision, in a device of the class described, of a unitary mechanism including a rockable coin or check discharger, a simple electromagnetic means for rocking the same, an especially contrived bracket means mounting the elements of said mechanism in unitary relationship on a coin stacking tube or the like, and a coin or check guiding chute also carried by said bracket means for directing coins or checks into the rockable discharger in the manner and for the purposes hereinafter more particularly specified.

Additional objects and aspects of utility and novelty pertain to details of structure and function of the preferred embodiment hereinafter described in view of the annexed drawings, in which:

Fig. 1 is a perspective view of the novel check separator and mounting means attached to a coin stacker tube, the latter shown in fragment;

Fig. 2 is a fragmentary side elevation, partly in section, of the upper or mouth portion of the coin stacking tube;

Fig. 3 is another perspective view of the separator unit similar to that shown in Fig. 1, but viewed from the opposite side shown in Fig. 1;

Fig. 4 is a fragmentary perspective view of parts shown in Fig. 3, with the coin or check discharger or deflector shown in actuated or advanced position.

In various types of coin-operated machines, it is often desirable to permit the operation thereof by either a legitimate coin or an authorized check or predetermined character and differing from the coin usually in diameter as well as metallic content; and it is desirable to separate the coins from the checks in the machine for purposes of collection and accounting, and to avoid the necessity of manually counting out or separating out the checks from the specie coins in the coin collection box or tube.

2

Devices for separating coins from checks, as aforesaid, are known in the art, but they do not have the features of flexibility, adaptability in mounting and detaching, simplicity and ruggedness of construction, ease of servicing, positive action, and reliability characterising the device disclosed herein.

Referring to Fig. 1, the novel unit includes a rigid upright 10 provided with a mounting clamp 11 at its foot secured by means of nut and bolt means 12 to the upper end portion 13 of a coin or check stacking tube or receptacle 14.

Clamp 11 is of U-shaped metal having the lower part of the upright 10 preferably spot-welded to the right portion thereof. At about the midportion of the upright 10, as seen by reference to both Figs. 1 and 3, is an angle bracket 15, secured to the upright as by spot-welding, one angle of this bracket having spot-welded thereto a second, elongated angle bracket 16 (Fig. 3) upon which is mounted by screws 17 and a third small angle bracket 18 supporting an electromagnetic solenoid 19.

A rockable coin discharger or directing means (Figs. 1 and 3) includes a lever arm 20 having an angular end projection 21 bent into a yoke or U-shaped bracket including a short angular offset arm portion 22 with aligned apertures in the latter arm portion and the lever arm body through which projects a pin 23 staked into the large angle bracket 16, so that said lever arm is pivoted in the region above the mouth of the stacking tube 14.

The lower or tail portion of the rocker lever 20 has staked therein a pin 24 removably attached, as by means 25, Figs. 1 and 3, to an end of a link 26 which has its opposite end pivotally attached as at 27 in the slotted end of the solenoid plunger 28 (Figs. 3 and 4), said plunger being normally disposed outward of the solenoid by spring means in the core thereof (not seen) so that said rocker lever 20 is disposed at a normal, lowered condition, as in Figs. 1 and 3.

Means for selectively receiving and holding a check or coin element, depending upon the diameter thereof, on the rocker lever or directing means, includes a shallow trough or tray portion 30, Fig. 3 particularly, having a circular coin or check passage 31 of predetermined diameter in the bottom thereof. Preferably, this trough is constructed from a flat piece of sheet metal pierced at its lower end to pass mounting screws 32 threaded into the yoke portion 21, opposite side portions of this piece being upset to provide side guards 33.

At the lower part of this trough is a small

angular foot or coin stop 34, preferably spot-welded, as at 35, to the lower portion of said metal piece from which the trough is formed; and at the upper end of the trough, there is spot-welded a bar 36 affording a coin stop at the upper end region of this trough.

The diameter of the hole 31 determines whether a coin or a check is to be retained in the trough upon delivery from a downwardly pitched guide 37 stamped from sheet metal parts rolled to form a closed tube of square cross section or rectangular section with the seam at the side indicated at 38, Figs. 1 and 3, there being an upset lip 39 for guiding coins gravitatingly into this chute guide, which is attached by a spot-welded bracket 40 to the upper portion of the main upright 10, so that the lower or discharge end of the guide chute confronts the upper end of the rockable trough means 30 to direct a coin or check into the latter.

If the check intended to be received in the device is of lesser diameter than the hole 31, it will drop through the latter and into the upper end and mouth of the stacker tube 14.

On the other hand, if the diameter of such check is greater than that of hole 31, as it may well be in certain cases, then such check would lie in the trough means 30 until the solenoid coil 19 is energized to draw the plunger means 28 thereof inwardly, retracting link 26, and rocking lever arm 20 about pin means 23, so that the trough portion 30 is elevated with a quick movement into the discharging position shown in Fig. 4, the coin or check, whichever, contained therein being thus sharply flung into space in an arc contained in the plane of movement of the rockable means and more or less concentric with the rocking axis at 23, to be received in a suitable wide-mouthed box or receptacle, not shown.

It is to be understood that the checks or the coins may be permitted to pass through the hole 31 and into the stacker 14, as desired, the device, however, normally being intended to handle a coin of a certain denomination and diameter, for example, a nickel, dime, or quarter, and a check of analogous size but slightly larger or smaller diameter than the corresponding coin. The embodiment shown is actually intended to retain a five-cent coin or nickel in the trough means 30, and to permit a smaller check to pass into the stacker 14; however, the reverse might be desirable, so that it is to be understood that whether the rockable means 30 holds a coin or a check and permits the substitute check or coin to pass into the stacker, is a matter of preference and not a limiting feature.

Various arrangements are employed for causing energization of the solenoid at desired times, as for example, immediately following the receipt of a coin element into the trough means; however, such arrangements are not shown here, it being sufficient to state that the solenoid or coil 19 is energized from any desired source or by any suitable means at the appropriate time to cause operation of the mechanism shown and described.

A further feature of the invention pertains to the means for preventing jamming of coins (or checks) in the stacker tube, such means being disclosed especially in Fig. 2, wherein it is observed that the upper end or mouth of the stacker tube 14 is sloped cross-wise of the axis of the tube; thus, as the coin elements indicated at C reach the upper extremities of the tube proper, subsequently deposited coins Cx will be deflected

out of the mouth of the tube, instead of piling up and jamming or blocking entrance to the tube and the region below the rocking parts.

Changes in the structural and functional features of the embodiment described in detail herein, for purposes of disclosure and illustration, will doubtless occur to those skilled in the art, and it is the intention to include all such changes within the scope of the invention as defined by the appended claims and fairly within the ambit of the disclosures which originate herein.

We claim:

1. Coin handling means including an upright stacker bracket means removably clamped to the upper end of said stacker, a rockable coin holding trough carried by said bracket means and having a passage aligned with the mouth of said stacker through which a coin element of lesser diameter than a coin intended to be received may pass into said mouth, electromagnetic means carried by said bracket means for rocking said trough from a normal position of alignment as aforesaid, to an elevated discharge position with energy sufficient to eject therefrom a coin element resting therein, and means carried on said bracket means for guiding coin elements into said trough.
2. Coin and check separating mechanism comprising a rockable trough having a coin passage of determined diameter in the bottom thereof, means normally supporting said trough at an inclined position such that a coin element larger than said diameter will rest therein, coin elements of lesser diameter passing through said passage, electromagnetic means for briskly rocking said trough from said normal position into an elevated position to fling a coin element resting therein outwardly therefrom, and means for guiding coin elements into said trough.
3. Coin and check separating mechanism comprising an upright tube having a non-jamming sloped mouth to receive coin elements for stacking in the tube, a bracket clamped to the tube adjacent said mouth, a pivoted coin receptacle carried by said bracket and normally inclined above said mouth so that a coin element will rest therein if said element is of a predetermined diameter, said receptacle having a coin passage in the bottom thereof of less than said predetermined diameter and aligned with said mouth such that coin elements of diameter small enough to pass therethrough will descend into said mouth, means carried by said bracket means for directing coin elements into said receptacle, solenoid means carried by said bracket and linked operatively with said pivoted receptacle to pivot the latter from normal to advanced position an amount to dislodge a coin resting therein outwardly thereof, responsive to energization of said solenoid means, said mouth being angled cross-wise of the axis of said tube to deflect surplus coins from the tube and prevent jamming at said mouth.
4. Mechanism of the class described including an upright, a U-shaped clamp at the foot of said upright for attachment to a stacker tube or the like, a solenoid and means attaching the same at a side of said upright with the plunger of said solenoid movable in an approximately horizontal sense, a coin guide carried at the top portion of said upright and opening in the general region above said foot for alignment with the entrance to said tube when attached as aforesaid, a coin receiver rockable about an approximately horizontal axis on pin means supported in a part of

said means attaching said solenoid to the upright, said receiver normally disposed at an inclination above said entrance when attached as aforesaid and formed to retain an intended coin and having a coin passage of predetermined diameter therethrough such that a coin element of lesser than intended-coin diameter may pass therefrom into said entrance, means operatively linking said solenoid with said rockable receiver and energizable to rock the latter from said normal disposition with force sufficient to dislodge a coin element retained therein and eject the coin element therefrom.
